CLAIM

The ornamental design for a pitching machine, as shown and described.

DESCRIPTION

FIG. 1 is a front, right and top side perspective view of a pitching machine showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the portion bounded by the dot-dashed lines of FIG. 2.

The dash-dash broken lines shown in the drawings represent portions of the pitching machine that form no part of the claimed design.

The dot-dash broken lines surrounding a portion of the pitching machine in FIG. 2 are present to identify the portion illustrated in the enlarged view in FIG. 9.
